Des. 647

S. W. Gibbs, of Albany, N.Y.
Assignor to
North, Chase & North of Philadelphia, Pa.
Letters Patent No. 647 - Dated May 9th, 1854.

The schedule referred to in these Letters Patent, and making part of the same.

To all whom it may concern.

Be it known that S. S. W. Gibbs, of Albany, in the County of Albany, and State of New York, have invented a new and improved design for gas ovens or summer ranges, and I do hereby declare that the following is a full & exact description thereof, reference being had to the accompanying drawings, and to the letters of reference marked thereon.

The design consists of a carved shield ^a raised on a panel, the panel being surrounded by a moulding. A, B are two dots to which this ornamental panel is applied. ^b is an ornamental moulding.

What I claim as my invention, and desire to secure by letters patent is, the ornamental panel ^a, and the ornamental moulding ^b, forming a design for gas ovens or summer ranges.
